(57) **CLAIM**

I claim the ornamental design for an electric connector, as shown and described.

DESCRIPTION

FIG. 1 is a front, top, and right side perspective view of an electric connector showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a cross section view thereof, taken along line 8-8 of FIG. 2; and,

FIG. 9 is a front, top, and right side perspective view thereof, in used condition.

The broken line in the figure drawings is included to show the unclaimed environment and forms no part of the claimed design.
